United States Patent [19]

Accumanno

[11] Patent Number: Des. 317,754

[45] Date of Patent: ** Jun. 25, 1991

[54] DOUBLE SWITCH ELECTRIC FAN CONTROL

D. 285,554 9/1986 Beaumont ..... D13/164 X
D. 307,587 5/1990 Marcune D14/159

[75] Inventor: Mario B. Accumanno, Cedar Grove, N.J.

Primary Examiner—Susan J. Lucas
Assistant Examiner—Joel Sincavage
Attorney, Agent, or Firm—Theodore Jay

[73] Assignee: SSMC Inc., Edison, N.J.

[57] CLAIM

[**] Term: 14 Years

The ornamental design for a double switch electric fan control, as shown and described.

[21] Appl. No.: 328,357

DESCRIPTION

[22] Filed: Mar. 24, 1989

FIG. 1 is a front isometric view of double switch electric fan control showing my new design;

[52] U.S. Cl. D13/162; D13/158

FIG. 2 is a left side elevational view of a double switch electric fan control showing my new design on a reduced scale;

[58] Field of Search ..... D13/158, 162, 169, 177; D8/350, 353; 220/241, 242; 174/66, 67; 200/11 R, 339, 553; D14/159

FIG. 3 is a top plan view thereof;
